JOHN C. LOVE, OF PHILADELPHIA, PENNSYLVANIA.*

Letters Patent No. 91,141, dated June 8, 1869.

IMPROVEMENT IN LAMP-BURNERS.

The Schedule referred to in these Letters Patent and making part of the same

To all whom it may concern:

Be it known that I, JOHN C. LOVE, of Philadelphia, Pennsylvania, have invented an Improved Lamp-Burner; and I do hereby declare the following to be a full, clear, and exact description of the same.

My invention consists of improvements in coal-oil lamp-burners, fully described hereafter, the improvements having been made with the view of rendering the flame more brilliant, gaining ready access to the wick, and easily adapting the burner to receive chimneys differing in size.

In order to enable others skilled in the art to make and use my invention, I will now proceed to describe its construction and operation, reference being had to the accompanying drawing, which forms a part of this specification, and in which—

Figures 1 and 2 represent exterior views of the two main parts of the lamp-burner, detached from each other;

Figure 3, a vertical section of the same, connected together;

Figure 4, an inverted plan view; and

Figure 5, a top view of the main portion of the burner.

Similar letters refer to similar parts throughout the several views.

The burner consists of the two main parts, A and B, the former of which is composed of a circular plate, *a*, and a hollow cylinder or dome, *b*, projecting from the said plate, the top of the dome being closed, with the exception of the usual elongated opening *d*.

To the annular rim *e*, projecting downward from the plate *a*, are secured three springs *f f f*, against the outer end of each of which bears the point of a set-screw, *h*, passing through the rim *e*, as best observed in fig. 4, and each spring has a finger, *i*, projecting upward through a slot, *j*, in the plate *a*.

By operating the screw *h*, the fingers, over which the glass chimney of the lamp fits, may be so adjusted as to be adapted to chimneys of different sizes. It is not essential, however, that all the fingers *i* should be adjustable, one movable finger sufficing to adapt the whole to different chimneys.

The portion B of the burner consists of a base, *m*, having the usual screw-projection *m'*, and carrying the flat-wick tube *k*, and the usual devices for operating the wick.

To this base is a perforated cylindrical or slightly-tapering casing, *n*, which is smaller in diameter than the dome, extends upward into the latter, above the wick-tube, and terminates in a flange, *p*, which fits snugly in the interior of the dome *b*, as best observed on reference to fig. 3.

Notches are cut in this flange, as seen in fig. 5, and these notches are so arranged that two of them, *q q*, shall be in line with the wick-tube, one at each end of the same.

On the base, *m*, are lugs *t t t*, arranged to so fit against the under side of the plate *a*, and against the interior of the dome, that while they serve to maintain the perforated casing *n* concentric with the dome, they are such as to permit the portion A of the burner to be readily detached from the portion B.

I have found that the nearer the perforated casing, into which air passes to the top of the wick, is to the flame, the better is the quality of the latter; hence, the placing of the perforated casing *n* within the dome B.

While the flange *p*, fitting snugly inside the dome, serves, with the lugs *t t t*, to render the upper portion of the burner a steady integral part of the lower portion, the upper portion, with its chimney, can be readily detached when access to the wick is necessary. At the same time, the notches in the steadyng-flange permit a plentiful supply of air to gain access to the interior of the dome above the wick, and the air passing through the notches *q q* of the flange, impinges against the edges of the flame, and renders the latter more brilliant.

I am aware that vertical fingers have heretofore been so secured to a lamp-burner as to be adjustable thereon, and I, therefore, do not claim, broadly, such adjustable fingers. But the devices hitherto used for adjusting the fingers have been complicated, and of such a character as to secure the fingers immovably in their position, after adjustment, thus causing the fracture of the chimney, should it contract.

By the device above described, a ready adjustment of the finger is effected, the fingers will move freely inward when the chimney contracts, while the cost of manufacturing the burner is not materially increased.

I claim as my invention, and desire to secure by Letters Patent—

1. The flange *p*, with its notches, at the upper end of the perforated casing *n*, in combination with the outer cone A and its slot *d*, all as described.

2. The combination of the springs *f*, their fingers *i*, and the set-screws *h*, all arranged on a burner operating as set forth.

In testimony whereof, I have signed my name to this specification, in the presence of two subscribing witnesses.

JOHN C. LOVE.
